YARN OILER FOR CONING MACHINES

Michael Morrell, Brooklyn, N. Y., assignor to
 Benjamin Brenner, Harry Brenner, Frank De
 Nicholas, and Michael Morrell, all of Brook-
 lyn, N. Y.

Application March 4, 1937, Serial No. 128,934

5 Claims. (Cl. 91—38)

This invention relates to yarn oiling devices, and has for an object to provide a construction which is an improvement over my prior Patent No. 1,953,863 filed April 22, 1932.

5 Another object of the invention is to provide an oiling device for threads or yarn wherein the flow of oil to the applying surfaces may be regulated.

Another object of the invention is to provide an oiling device for yarn wherein the applying surfaces may be adjusted to produce more or less friction on the yarn being oiled.

Another object is to provide guides or holders adapted to hold a felt oil distributing member in functioning position.

15 In the accompanying drawing:

Fig. 1 is a perspective view of a yarn oiler disclosing an embodiment of the invention;

Fig. 2 is a sectional view through Fig. 1 approximately on the line 2—2, the same being on an 20 enlarged scale;

Fig. 3 is a transverse sectional view through Fig. 2 on the line 3—3;

Fig. 4 is a fragmentary vertical sectional view through Fig. 2 approximately on the line 4—4;

25 Fig. 5 is a sectional view through Fig. 1 on line 5—5, the same being on an enlarged scale.

Referring to the accompanying drawing by numerals, 1 indicates posts or uprights forming part of the coning machine, although they could form parts of other devices. The various brackets 2 are secured to the posts 1, although they could be supported by some other means, if desired. The brackets 2 may be made in two parts and clamped together by the bolts 3, as shown in Fig. 2. It will be understood that hook-shaped extensions 4 surround part of the respective posts 1 so that when the bolts 3 are tightened the brackets will be clamped tightly to the posts 1.

40 Arranged on top of the various brackets 2 so as to be supported thereby is a container or tank 5 preferably of sheet metal, although it could be formed of some other material. Suitable clamping bolts 6 extend through the bottom of this container and through the various brackets 2 so that whenever the winged nuts 7 are tightened the container will be clamped firmly in place. The container 5 is open at the top for its full width and length. However, there is provided a 45 lid 8 which has depending walls adapted to telescope over the upper part of the container 5, as shown particularly in Fig. 2. As shown in Fig. 1, there are a number of felts 9 arranged at spaced intervals along the container, but as each 50 55 felt and associated part is identical with the

other felts and associated parts the description of one will apply to all.

As shown in Fig. 2, the felt 9 has a depending part 10 more or less submerged in the oil 11 arranged in container 5. The felt 9 is any desired grade of felt which will permit the oil to move by capillary attraction upwardly and then horizontally to what may be termed the felt jaws 12 and 13. A clamping bar 14 extending entirely across the felt is arranged beneath the felt 9 adjacent the point where it bends, and a suitable bolt 15 having a winged nut 16 is used for manipulating the bar 14. As shown in Fig. 2, the bar 14 is arranged between the abutment 17 and the head 18 of bolt 15 whereby as the bolt is moved upwardly or downwardly bar 14 will be moved accordingly. This bar acts as a valve for regulating the flow of oil from the section 19 to the jaws 12 and 13. When the bar 14 presses lightly against the felt, a large supply of oil is provided for the jaws 12 and 13, but if the nut 16 was tightened and the bar 14 moved upwardly until the felt was compressed to a considerable extent, only a small amount of oil would flow. By regulating this bolt the flow of oil may be also regulated or stopped. The yarn 19 extends through the split or opening 20 between jaws 12 and 13. These jaws are arranged sufficiently near to each other to not only supply oil to the yarn 19 but to move lint and other objectionable matter therefrom as the yarn travels upwardly. In case the jaws scrape off some comparatively large quantity of waste or other foreign particles, an operator may readily open the jaws and remove this waste matter without stopping the coning structure.

It will be noted that the jaws 12 and 13 fit into holding clamps 21 and 22. Both of these clamps are U-shaped in cross section and holding clamp 21 is preferably welded or otherwise rigidly secured to the cover 8, but could, if desired, be pivotally mounted on the cover, while the holder 22 is pivotally connected with the cover 8 by a bolt or rivet 23. Pins 24 and 25 extend through the respective holders and through the respective jaws, as shown in Fig. 3, whereby the jaws will move with the holders. Holder 21 will hold the jaw 12 stationary, but holder 22 may be swung toward and from holder 21 and consequently cause jaw 13 to move toward or from jaw 12. Holder 22 is provided with a curved thumb member 26 whereby the operator may at any time press on this thumb member and open the jaws. A compression spring 27 bears against the holder 22 and against a stop 28 so as to continually urge holder 22 toward

holder 21. A bolt 28 has a winged nut 30 which may be actuated for pulling the holder 22 away from holder 21 or actuated for releasing holder 22 so that spring 27 may force the jaws toward each other. In case of wear of the jaws, winged nut 30 may be adjusted to compensate for this wear and consequently permit the jaws to press with a continuous even pressure on the yarn as it is pulled through the jaws. As shown in the drawing, the yarn moves upwardly from a supply and passes between the jaws and then to means for winding the yarn on a cone. In using silk and other yarn it is desirable to apply oil thereto in order that the fibers may be arranged substantially parallel as the yarn is used in knitting machines, looms, and the like.

The container 5 may have a suitable drain at any desired point and the cover of the lid 2 is provided with an inlet opening 31 which is covered by a swinging lid 32. Lid 32 may be clamped closed by the swinging nut 33 so as to prevent dust and the like from entering the container. At the opposite end of the container to the opening 31 is provided a gauge 34 which may be of any desired kind and which indicates the level of oil in the container. The nut 33 acts on a clamping bolt 35 carried by a cross piece 36 shown in Fig. 5. A nut or other abutment 37 coats with the head 38 for rotatably securing the bolt 35 to the container 5. When the winged nut 33 is tightened it will not only clamp the swinging lid 32 in place, but will clamp the telescoping lid or cover 8 against removal.

I claim:

35. 1. A yarn oiler including a container adapted to receive a quantity of oil, a felt extending from said container and arranged so that one end will be submerged in said oil and the other end slit at the part extending beyond the container, said slit part presenting a pair of jaws through which a yarn is adapted to pass as oil is applied thereto by the felt, a stationary holder for one of said jaws, means for connecting the stationary holder to the jaw mounted therein, a swinging holder, means for connecting the other jaw to said swinging holder, means including a spring for forcing said swinging holder toward the opposite holder, and thumb actuating means for moving said swinging holder against the actuation of said spring.
40. 2. A yarn oiler including a container adapted to receive oil, a plurality of spaced L-shaped felt members positioned so that one leg of each felt member will be in said oil and the other projecting horizontally from the container, the projecting part of each felt being slit to provide jaws
45. 3. A yarn oiler including a container adapted to receive oil, a felt member extending from said container and having a pair of jaws, a stationary holder for one of said jaws, a pin extending through said holder and the jaw carried thereby for securing the jaw to the holder, a holder for swinging the other jaw toward and from the stationary jaw, a pin extending through said other jaw and its holder for securing the other jaw to its holder, said last mentioned holder being pivotally mounted at one end, a spring near the opposite end for swinging the holder toward the stationary jaw, a stationary bracket and a retractile bolt member acting against said bracket for moving the swinging holder against the action of said spring.

between which the yarn being oiled is adapted to pass, a holder for holding one of said jaws stationary, a pin extending through said holder and the jaw carried thereby for securing the jaw to the holder, a holder for swinging the other jaw toward and from the stationary jaw, a pin extending through said other jaw and its holder for securing the other jaw to its holder, said last mentioned holder being pivotally mounted at one end, a spring near the opposite end for swinging the holder toward the stationary jaw, a stationary bracket and a retractile bolt member acting against said bracket for moving the swinging holder against the action of said spring.

3. A yarn oiler including a container adapted to receive oil, a felt member extending from said container provided with a slit end, said slit end projecting from the container and forming a pair of facing jaws, a stationary holder substantially U-shaped in cross section for one of said jaws, means for connecting one of said jaws to said stationary holder, a movable jaw substantially U-shaped in cross section fitting over most of the other jaw, means at one end of the movable holder for pivotally mounting the same, a thumb member at the end opposite the point where the movable member is pivotally mounted, a spring for swinging the movable member and jaw carried thereby towards the stationary jaw, an abutment, and a bolt carried by the movable member acting on the abutment for pulling the movable member away from the stationary jaw against the action of said spring.

4. In a yarn oiler, a felt having a slit end forming a pair of jaws, means for holding one of said jaws stationary, a swinging holder for the other of said jaws, a pin for connecting the other of said jaws to the swinging holder, spring means for moving the swinging holder and jaw carried thereby towards the stationary jaw, and a bolt for swinging the swinging holder away from the stationary jaw and at the same time pulling the jaw carried thereby away from the stationary jaw.

5. In a yarn oiler, an oil container, pairs of felt holders carried by said container, each pair of holders comprising a stationary holder and a movable holder, a felt for each pair of holders, said felt having a stationary jaw and a movable jaw, a pin for each of said jaws for connecting the respective jaws to the respective holders, and means for adjusting one holder of each pair toward the other for moving said jaws toward or from each other according to the direction of adjustment.

MICHAEL MORRELL.
